UNITED STATES PATENT OFFICE

154,871

DESIGN FOR A HELICOPTER

Arthur W. Nelson, Niagara Falls, N. Y., assignor
to Bell Aircraft Corporation, Wheatfield, N. Y.

Application August 22, 1947, Serial No. 141,003

Term of patent 14 years

(Cl. D71—1)

To all whom it may concern:

Be it known that I, Arthur W. Nelson, citizen of the United States, residing at 962 Rankine Road, Niagara Falls, New York, have invented a new, original, and ornamental Design for Helicopter, of which the following is a specification, reference being had to the accompanying drawing, forming part thereof.

Fig. 1 is a top plan of a helicopter, showing my novel design;

Fig. 2 is a side elevational view thereof; and

Fig. 3 is a front end elevational view thereof.

Fig. 4 is a side elevational view thereof on a larger scale, showing the compartment cover device in closed position; and Fig. 5 is a view similar to Fig. 4, but showing the cover device in opened position.

The characteristic features of my design reside in the portions shown by means of full lines in the drawing; and the dotted line showing of the articles on the inside of Fig. 5 are shown for

purely illustrative purposes. The showings in Figs. 4 and 5 are of fragmentary portions of the helicopter, and are for the purpose of more particularly showing the compartment units thereof.

I claim:

The ornamental design for a helicopter, as shown and described.

ARTHUR W. NELSON.
